UNITED STATES PATENT OFFICE

EDMUND O. SCHWEITZER, OF CHICAGO, ILLINOIS

LIGHTNING ARRESTER

Application filed May 23, 1927. Serial No. 193,443.

My invention relates to current interrupting devices, and while the invention is particularly useful in connection with lightning arresters employed to provide a path to ground for excessive transient voltage conditions on power circuits and the like, and I have shown the preferred embodiment as employed in such use, it is not to be limited to such use.

I am aware that it is old to provide a horn gap arrester with one horn connected directly to the line and the other grounded through a water resistance for limiting the dynamic flow. In the preferred embodiment of my invention I employ those elements but now arranged in a novel relation and for a novel purpose.

The current flow which maintains the arc is employed at the same time in the water resistance to generate a vapor which is usefully employed to extinguish the arc.

It is desirable to project the vapor with considerable violence into the space where the arc is maintained so as to secure both a quick and complete occupation of the space at one time, and also to sweep the arc away from the position where it maintains itself. The vapor should be permitted to expand to become dry and to increase the velocity of the same. The manner in which this is secured and the apparatus by which it may be done is explained more in detail in the following specification, in which I have illustrated an embodiment of the invention in order to teach those skilled in the art how to construct and operate the same.

In the drawings,

Fig. 1 is a diagram of a system embodying my invention;

Fig. 2 is a similar diagram of a modification of the same;

Fig. 3 is a diagrammatic view of two elements embodying my invention connected in series; and

Fig. 4 is a diagram of another modification.

Referring now to Fig. 1, the line conductor 1 is a phase conductor of a power distribution or transmission system, and the lightning arrester 2 of my invention is connected to said

line and provides an interrupted novel path to ground at 3 for the purpose of providing a discharge path to ground for abnormal transient voltages, but to break the dynamic flow of current which would tend to follow. The lightning arrester includes a horn gap 4 comprising the horn electrodes 5 and 6 consisting of divergent upwardly extending members having a minimum gap at 7 where the divergent members approach each other closely. These horn electrodes are supported on insulators 8 and 9 on the tank 10, which tank may be made of suitable sheet metal, such as boiler plate or the like, to withstand considerable pressure. The horn electrode 5 is connected to the line wire 1 and is therefore live at all times that there is potential on the line wire 1. The horn electrode 6 is connected to ground at 3 through a water resistance contained in the tank 10. This water resistance comprises a body of water 11 which is maintained normally at a level, such as indicated at 12, through the medium of a float controlled valve 13 connected in a supply line 14, as for example from the city water mains. The float chamber 15, which controls the level in the tank 10, is connected to said tank 10 through a pipe connection including the check valve 16. The circuit of the grounded electrode 6 includes a pair of spaced electrodes 17 and 18 within the tank 10 and preferably disposed in such relation within the tank that the gases and vapors, due to the passage of a current through the water between these electrodes, is quickly freed at the surface of the water and may discharge through the discharge pipe 19 and nozzle 20, which nozzle is disposed adjacent the minimum gap 7 of the horn electrodes 5 and 6. This nozzle is preferably a flattened oblong opening, such as would be produced by squeezing together the two sides of a pipe to form a relatively narrow slit as an outlet. The pipe 19 and nozzle 20 are preferably made of a piece of bakelite or other suitable insulating material. The gases and vapors which are formed by the passage of current from the electrodes through the water between them, rise to the upper part of the tank 10 and are discharged through the pipe 19 and

nozzle 20 into the gap between the horns 5 and 6 in such a manner as to release the steam and gas at a point where it will occupy the space in which the arc must be maintained. The nozzle 20 forms a restriction producing a higher velocity of the vapor when it emerges into the open air and flows into the horn gap. Since the vapor is projected into free atmosphere from the nozzle 20 it has an opportunity to expand and become dry and, therefore, highly efficacious for extinguishing the arc. The increased velocity produced by the expansion is highly desirable. The greater the power flowing through the arc, the greater will be the tendency to project gas and vapor into the space where the arc is maintained to extinguish the same. The action of the vapor and gases discharged from the nozzle 20 is two-fold. First, the violence of discharge tends to blow the arc upwardly along the horns 5 and 6, stretching the same and tending to break the arc. Second, the gases and vapors are relatively high in insulating quality and tend, by their presence in the space in which the arc is maintained, to cool the arc and to increase the resistance of passage of the arc through the space to such an extent as to extinguish the same.

The operation of the device is remarkably quick, as has been demonstrated by photographic records of the operation of the same. The initial rush of current from the line 1 finds a relatively easy path to ground, excepting the air gap at 7. If the disturbance is great enough to break down the air gap, the current flows to ground through the water gap 17-18, there releasing, by the heat of current flow, a vapor which is discharged through the nozzle 20 and which quickly breaks the arc at this point.

I have shown the lower end of the tube 19 as extending adjacent the surface of the water. It is within my invention to extend the same down to a point below the surface of the water for the purpose of securing a puff or blast of greater violence. The manner in which this is accomplished will be apparent from the fact that if the lower end of the pipe 19 is extended to a point below the normal level 12, the pressure in the upper part of the tank 10 must be raised to a point great enough to eject a slug of water before steam can enter the pipe 19, and as the pressure builds up with great rapidity in said tank 10, such pressure is not released until it has reached a relatively high point to give a violent puff or blast. The initial discharge of a slug of water has no adverse influence on the operation of the device because no conducting body or surface connects the horn electrodes 5-6 and the water or the interior electrodes 17-18.

I have shown the ground circuit as including the wire 21 led into the interior of the tank 10 through an insulator 22 and there

connected to the electrode 18. The electrode 17 is connected through a wire 23 extending through an insulator 24 to ground at 3. If desired, the bank itself may be grounded and may comprise one side or electrode of the water gap.

It will be observed that the electrodes 17 and 18 are projected above the normal level of the water 12 and where this is done, I find that the vapor appears to be formed mostly at the surface and is thereby released with great rapidity. The check valve 16 prevents discharge of water out of the tank 10 and, after an operation of the device to extinguish an arc, any water which has been displaced by the action is replaced from the supply line 14 to the float controlled valve 13.

If desired, a heater may be employed during cold weather to maintain a suitable temperature of the water in the tank 10, and the water may be changed periodically, as by draining out a certain part of the same through a drain connection 25.

In Fig. 2 I have shown a modification in which the electrodes 17 and 18 are disposed within a supplementary chamber 27 within the tank 10. This supplementary chamber 27 is connected at its upper end to the pipe 19 and nozzle 20, and is open at its lower end to the tank 10, a suitable check valve 28 being shown as controlling disconnection, but this check valve may be dispensed with due to the tampering action of the body of water in the tank 10. The level 12 stands normally the same in the main tank 10 and in the supplementary chamber 27, and the electrodes 17 and 18 are arranged, as above referred to in connection with Fig. 1, adjacent the surface of the water, but within the chamber 27. Upon the breaking down of the gap 17 and the flow of current through the wire 21 from electrode 18 to 17 and to ground through wire 23, vapor is generated within the chamber 27 and is immediately expelled through the pipe 19 and nozzle 20 into the gap between the horn electrodes. This results, as before, in a quick and positive snuffing or extinguishing action.

In Fig. 3 I have shown how a plurality of such arresters may be connected in series where the voltage to be controlled is greater than would be within the scope of a single unit. The two units shown in Fig. 3 are identical and are substantially of the same general character as shown in connection with Figs. 1 and 2. A supplemental chamber 27' is employed at the lower end of the tube 19, which in this case is extended down to such chamber 27' considerably below the level 12 of water in the tank 10. The electrodes 17 and 18 are disposed in said supplemental chamber 27'. The lower end of the chamber 27' is, in this case, left open to the space within the tank 10 outside of the chamber 27'. The action of each unit is the same as previ-

ously described, the two units operating simultaneously. The chamber 27' being disposed at a considerable depth below the level 12, is normally full of water as is the lower part of the pipe 19. As a result, the generation of vapor and gases in the chamber 27' is not immediately released, the same being held under the head of liquid in the pipe 19 until the same is ejected, whereupon, the 10 gases and vapors are released with considerable violence at the nozzle 20.

I have shown the circuit as insulated from the tanks 10—10, but, as previously explained, the tanks being preferably of metal, 15 may be included as a part of the circuit. I find it desirable to support the tanks on insulators, particularly where a plurality are used as shown in Fig. 3.

In Fig. 4 I have shown a modification in which the tank 10 is provided with a tube 30 which projects down through the top wall of the tank. This tube 30 communicates at its lower end with the interior of the tank 10, in this case a check valve 31 being employed, said check valve preferably being formed of metal. A rod 32, extending from the horn, projects down inside of the tube 30, forming an electrode. The tube 30 is preferably formed of insulating material and has 35 its upper end formed into a nozzle so that the vapor which is released upon the flow of current through the electrode 32 through the liquid, will be discharged into the gap between the horn electrodes 5 and 6, to extinguish the arc. The principle is the same as disclosed in the previous modification, the 40 mechanical embodiment being different. In each form there is an air gap and a water gap with means arranged to take the vapor formed at the water gap and discharge it into the air gap. By this means the same flow of energy which passes through the air gap also passes through the water gap and, as is well known, the greater the energy being released in an arc, the more difficult it is to extinguish, but, at the same time, the more energy passing through the 45 water gap, the greater power does it have to perform the act of extinguishing the arc.

I have tried the experiment of projecting only water into the horn gap and I find that, within the normal limits of energy available, the flashing of the water into steam within the space in which the arc is formed, is not as satisfactory as projecting the vapor itself after it is formed. I consider that the reason for this is, first, that it is more difficult to secure the same velocity of flow of the heavier liquid than it is of the lighter vapor; second, that unless the energy is great enough to flash the water immediately into steam, the projection of a stream of water through the 50 arc space in the horn gap merely maintains a conducting path, so long as the stream of water is maintained. This is not true, how-

ever, where a stream of gas or vapor is projected into the horn gap, as it has already been transformed from a liquid conducting state to a gaseous non-conducting state, and the discharge of vapor may continue long after the arc has been extinguished without again establishing the arc. This would not be true in the case of water.

The water which I have employed in my operation of the device above described, is city tap water taken from the Chicago mains. It contains sufficient mineral to provide the necessary conductivity without too great conductivity for my purposes. It is obvious to those skilled in the art that the size and spacing of the electrodes 17—18 is dependent upon the voltage and energy available and the conductivity of the liquid and like factors which are known to affect a water resistance.

It is to be observed that the initial path for the discharge of the transient voltages has relatively great capacity and yet includes considerable resistance. The resistance is great enough to prevent excessive flow of dynamic current, but, at the same time, the resistance to the flow of dynamic current is very rapidly increased by the generation of vapors and gases between the electrodes 17 and 18.

It is not essential that automatic float control valve be employed for maintaining a definite level, since the device of my invention will work within a wide variation of levels and a periodic filling of the tank 10 is all that is normally required.

In all of the forms shown a part of the liquid is subjected to heating by the flow of current. Vapor is formed and projected through a nozzle into a free atmospheric space, the nozzle being directed into the space between the horn electrode where the arc occurs. The nozzle causes an increased velocity and secures drying of the vapor by a speedy expansion and gives the expanding stream of vapor the desired direction in free space.

I do not intend to be limited to the details shown and described.

I claim:

1. In combination, a spark gap, a relatively small liquid tank having a pair of electrodes, a body of water in the tank disposed between said electrodes, said electrodes being connected in series from the spark gap to ground, a nozzle connected to the tank and spaced from and directed into the spark gap for conducting vapor from said tank and discharging the same into the spark gap, and a relatively large tank within which the small tank is immersed and which supplies water to the small tank.

2. In combination, a spark gap comprising a pair of electrodes, a chamber, a pair of electrodes in the chamber, a body of water

in said chamber between the electrodes, a discharge connection from the chamber leading to the spark gap for discharging vapors released in said chamber into the spark gap, and a tank surrounding said chamber and communicating therewith to maintain the chamber full of liquid.

3. In combination, a main tank, a chamber within said tank communicating with the main tank, electrodes in said chamber, a spark gap in series with said electrodes, a discharge conduit leading from the chamber to the spark gap, and a body of liquid in said tank and in said chamber between the electrodes.

4. In combination, a spark gap comprising free horn electrodes in the open atmosphere, insulators for supporting said electrodes, a nozzle extending toward the gap between the electrodes, but out of contact with the electrodes and having a restricted opening directed into the space between the electrodes, a water chamber connected to said nozzle, and a pair of electrodes in the water chamber connected in series with the horn electrodes.

5. In combination, a spark gap, a tank adapted to contain a conducting liquid, electrodes adapted to be connected by the liquid in the tank, said spark gap and electrodes being connected in series relation, said tank having a restricted outlet spaced from the spark gap and adapted to direct a flow of vapor into the spark gap to extinguish an arc, there being free expansion space between the said outlet and the spark gap.

6. In combination, a spark gap, a tank containing a conducting liquid, a pair of electrodes in the tank, said electrodes extending above the level of the liquid in the tank and being connected in series relation with the spark gap, and a nozzle for projecting vapor from the tank and produced from the liquid in the tank into the spark gap.

7. In combination a closed tank adapted to contain liquid, means for passing an electric current through the liquid to decompose and vaporize a portion thereof, an exposed spark gap mounted for permitting the free passage of air into and away from the region of the gap to tend to maintain the pressure at the gap at atmospheric pressure, said gap comprising a pair of exposed electrodes, means for supporting the same, and means for violently ejecting the products of the decomposition and vaporization of the liquid into the open atmosphere in the region of the spark gap, said means including a nozzle of insulating material extending substantially to the spark gap and directed into the region of the gap.

8. In combination a closed tank adapted to contain liquid, means for passing an electric current through the liquid to decompose and vaporize a portion thereof, an exposed spark

gap mounted for permitting the free passage of air into and away from the region of the gap to tend to maintain the pressure at the gap at atmospheric pressure, said gap comprising a pair of exposed electrodes, means for supporting the same, means for violently ejecting the products of the decomposition and vaporization of the liquid into the region of the spark gap, said means including a nozzle of insulating material extending substantially to the spark gap and directed into the region of the gap, and said spark gap supporting means being mounted on the tank.

9. Arc interrupting means including a pair of arcing members and a steam generator comprising a relatively large water chamber having a relatively small supplementary chamber therein and extending above and below the water level in the large chamber, said supplementary chamber having an opening for permitting the entrance of water therein from the large chamber, means within the small chamber for generating steam, and a steam outlet for said supplementary chamber, said outlet being directed into the region of the arcing members.

10. Arc interrupting means including a pair of arcing members and a steam generator comprising a relatively large water chamber having a relatively small supplementary chamber therein and extending below the water level in the large chamber, said supplementary chamber having an opening for permitting the entrance of water therein from the large chamber, means within the small chamber for generating steam, a steam outlet for said supplementary chamber, said outlet being directed toward the arcing members, and means for checking the expulsion of water through said first mentioned opening upon a rise in pressure within the supplementary chamber.

In witness whereof, I hereunto subscribe my name this 18th day of May, 1927.

EDMUND O. SCHWEITZER.
